DESIGN FOR A COMBINED SETTING AND JEWELS

William Simon, Clifton, N. J., assignor to B. F.
Hirsch, Inc., New York, N. Y., a corporation
of New York

Application January 14, 1939, Serial No. 82,352

Term of patent 14 years

To all whom it may concern:

Be it known that I, William Simon, a citizen of the United States and a resident of Clifton, county of Passaic, and State of New Jersey, have invented a new, original, and ornamental Design for a Combined Setting and Jewels, of which the following is a specification, reference being had to the accompanying drawing, forming a part thereof, wherein:

Figure 1 is a top plan view of the combined
setting and jewels showing my new design;

tion on the broken line 3—3 of Figure 1.

I claim:

The ornamental design for a combined setting
and jewels, substantially as shown.

WILLIAM SIMON.
